Patented Oct. 7, 1919.

UNITED STATES PATENT OFFICE.

LAUREN J. WHEELER AND HARLAN R. ROBBINS, OF SALT LAKE CITY, UTAH.

PROCESS OF AND APPARATUS FOR THE CONCENTRATION OF GRAPHITE ORES.

1,318,003.

Specification of Letters Patent.

Patented Oct. 7, 1919.

Application filed December 31, 1917. Serial No. 209,725.

To all whom it may concern:

Be it known that we, LAUREN J. WHEELER and HARLAN R. ROBBINS, citizens of the United States, residing at Salt Lake City, 5 in the county of Salt Lake and State of Utah, have invented certain new and useful Improvements in Processes of and Apparatus for the Concentration of Graphite Ores, of which the following is a specification.

- 10 Our invention relates to an apparatus for the concentration of graphite ores, in a dry state; in other words, the object of the invention is to separate graphite from gangue materials with which it is associated and to 15 do this by a combination of effects which take advantage of the difference in cohesion, weight, resilience and shape of the particles of graphite and the gangue minerals with which the graphite is usually found.
- 20 With the above and other objects in view, our invention consists of the process, and the parts and the constructions, arrangements and combinations of parts which we will hereinafter describe and claim.
- 25 It is well known that graphite is a sectile mineral of comparatively low resilience while quartz, feldspar, and such materials which are the main impurities of graphite ores, are resilient to a greater degree than 30 graphite.

In carrying out the invention we may use our process in connection with different types of apparatus. Hence the process portion of the invention is not to be understood 35 as restricted to the specific mechanism hereinafter described, and to the precise character of apparatus shown and which may be treated as embodiments of mechanism which will be found useful in working the process.

40 In the accompanying drawings—

Figure 1 represents a vertical cross sectional view of a graphite machine embodying our invention.

Fig. 2 is an end view of Fig. 1.

45 Fig. 3 illustrates a further embodiment of mechanism by which our invention can be carried out.

In the type of machine illustrated in Fig. 1, A represents a feeding mechanism of the 50 endless-belt type and which is designed to operate below the mouth or discharge of a storage bin, A', containing the material to be treated, the feeder delivering said material through an opening in the upper portion 55 of an appropriate casing, B', which forms a housing or inclosure for a drum, B, to

which rotary motion is communicated by pulleys or otherwise, and the surface of which drum may be plain or rough and may be of iron, wood, glass or fabric, as will 60 be found best suited for our purposes, said drum being designed to be rotated in the direction of the arrow, C.

The lower portion of the casing, B', is formed with separate hopper-shaped portions, F—H one of which is designed as a receiver for the gangue, or waste material, and the other a receiver for the separated graphite, these hopper-like portions having depending tubes or being otherwise provided with outlets for the discharge of the 65 material received into the hoppers.

In the upper portion of the chamber in which the drum rotates and mounted on the casing at a point to one side of the vertical 70 center thereof and of the rotating drum, is a vertically-disposed baffle, E, the width of which is approximately equal to that of the drum, said drum being provided with end flanges, D², between which the ends of the 75 baffle are located. The baffle is connected to a screw or appropriate means by which it may be raised and lowered relatively to the surface of the drum.

In the lower portion of the casing, say 80 about midway between the hopper portions thereof is disposed a wiper, G, of suitable material and which projects upwardly into the chamber of the shell and into contact 85 with the surface of the rotating drum. 90

As before stated, our invention comprehends a process wherein the separation of the graphite from the gangue minerals is effected by taking advantage of the difference in cohesion, weight, resilience and shape 95 of the particles of graphite and gangue minerals, and in the carrying out of the process we feed the material from the storage bin onto the declining surface presented by the circumference of the drum. This delivery 100 of the material upon the surface of the drum is at a point to one side of the vertical longitudinal center of said drum, and the said drum is rotated at a sufficient speed to cause the formation of an air-film thereabout and 105 as the material is dropped upon the drum, the graphite particles will either adhere to the surface of said drum or will be caught in and carried around by the air-film, and beneath the lower edge of the baffle and past 110 the vertical center of the drum and will finally be delivered over the other side of the

drum and into the hopper or bin, F, provided for the purpose. Any graphite which might adhere to the surface of the drum will be engaged by the wiper G and removed and 5 directed into said bin.

The gangue minerals forming part of the original feed upon coming in contact with the surface of the drum will, because of their greater resilience rebound beyond the air- 10 film and into the space formed between the drum and the inner wall of the casing and will drop into the hopper or bin, H; and any gangue minerals which may be caught up by the air-film which circumscribes the drum 15 will be swept from the surface of the latter on coming in contact with the lower edge of the interposed baffle, and thus will be thrown back and finally directed into the said bin or hopper, H.

20 The graphite particles of the feed which have less resilience and weight, but greater cohesion than the gangue particles and which graphite particles are caught up by the air-film, come in contact with the baffle, 25 E, but do not rebound. Rather they drop onto the surface and remain thereon and are carried around beneath the baffle to the other side of the center of the drum and thence they drop into the hopper, F, or are detached 30 from the surface by means of the wiper, G. The flanges with which the ends of the drum are provided serve to prevent the particles of ore from rolling off the side or ends of the drum.

35 The strength of the air-film before described may be regulated by the speed at which the drum is rotated. If the drum is rotated very slowly there will be practically no air-film and the apparatus just described 40 will work by the action of the cohesion of the particles and consequently when the feed is dropped onto the surface of the drum, the graphite or material of less resilience but greater cohesive power will adhere to the 45 surface of the drum and be carried over into the hopper, F, while the gangue minerals being more resilient and less cohesive, will rebound and slide down the surface of the drum into the bin or hopper, H.

50 The method hereinbefore described may also be carried out in all of its essential steps by the simple mechanism in Fig. 3. In this case, the ore is fed from an appropriate feeder, A², upon the upper portion of an inclined surface and which surface may be of such materials as we have heretofore referred to, as constituting the surface of the drum. At the lower end of this inclined surface, B², are placed the bins or hoppers, D², 55 which are spaced an appropriate distance below the delivery end of the incline, and which end is also positioned slightly back or to one side of the division line between the two hoppers or bins shown for 60 illustrative purposes. As the material is de-

livered upon the upper portion of the inclined surface and which surface may be either stationary or vibratory, the gangue minerals or those parts which have the greater resilience will rebound from said 70 surface and will be delivered into the bin or hopper, D², while the graphite particles will either adhere to the inclined surface, or slide down this surface and off the lower edge thereof and into the receptacle, D³.

75 The gangue minerals which have rebounded have attained such a speed in rolling down the inclined plane that they will come off the edge thereof at a greater distance than the graphite particles, and, therefore, can be separated therefrom without serious difficulty.

80 From the foregoing description it will be understood that when employing either of the mechanisms shown or any other equivalent parts, the sand and other hard impurities with which the graphite is originally associated will, upon striking the inclined surface either make a series of jumps down the plane or roll more rapidly thereover than the graphite will slide, and will, therefore, 85 be carried farther from the lower edge of the inclined plane of Fig. 3, or will rebound from the inclined surface of the drum of Fig. 1, so as to be capable of collection in a separate receptacle.

90 Having thus described our invention what we claim as new and desire to secure by Letters Patent is:—

1. An ore separator comprising a substantially closed casing, a drum inclosed by and mounted to rotate therein, means for operating the drum to induce an air-film in proximity to the surface thereof, means for feeding material to be separated onto the surface of the drum, said air-film attracting 100 to the surface certain constituents of the ore, and said surface causing the other constituents of the ore to rebound therefrom out of the sphere of action of the air-film, and separate receivers for the separated particles 105 of the ore mass.

2. An ore separator comprising a substantially closed casing, a drum entirely inclosed by and mounted to rotate therein, means for operating the drum to induce an air-film in 115 proximity to the surface thereof, means for feeding material to be separated onto the surface of the drum, said air-film attracting to the surface certain constituents of the ore, and said surface causing other constituents 120 of the ore to rebound therefrom out of the sphere of action of the air-film, and separate receivers for the separated particles of the ore mass, said casing having a feed inlet in the upper portion and said receivers being 125 formed in the casing below said drum.

3. An ore separator comprising a casing, a drum mounted to rotate therein, means for operating the drum to induce an air-film in proximity to the surface thereof, means for 130

- feeding material to be separated onto the surface of the drum, said air-film attracting to the surface certain constituents of the ore, and said surface causing the other constituents of the ore to rebound therefrom out of the sphere of action of the air-film, separate receivers for the separated particles of the ore mass, and a baffle in advance of the vertical center of the drum arranged adjacent the periphery of the upper portion of the drum and beneath the lower edge of which the adhering particles pass to the opposite side of said drum, said baffle extending substantially the entire width of the drum.
4. An ore separator comprising a casing, a drum inclosed by and mounted to rotate therein, means for operating the drum to induce an air-film in proximity to the surface thereof, means for feeding material to be separated onto the surface of the drum, said air-film attracting to the surface certain constituents of the ore, and said surface causing the other constituents of the ore to rebound therefrom out of the sphere of action of the air-film, separate receivers for the separated particles of the ore mass, and a baffle arranged adjacent the periphery of the upper portion of the drum and beneath the lower edge of which the adhering particles pass to the opposite side of said drum, said drum having end flanges contiguous to which the ends of the baffle terminate.
5. An ore separator comprising a casing, a drum mounted to rotate therein, means for operating the drum to induce an air-film in proximity to the surface thereof, means for feeding material to be separated onto the surface of the drum, said air-film attracting to the surface certain constituents of the ore, and said surface causing the other constituents of the ore to rebound therefrom out of the sphere of action of the air-film, separate receivers for the separated particles of the ore mass, a baffle extending substantially the width of the drum and arranged adjacent the periphery of the upper portion of the drum and beneath the lower edge of which the adhering particles pass to the opposite side of said drum, said drum having circumferential flanges disposed adjacent the ends of the baffle and means for vertically adjusting the baffle relatively to the surface of the drum.
6. An ore separator comprising a casing, a drum mounted to rotate therein, means for operating the drum to induce an air-film in proximity to the surface thereof, means for feeding material to be separated onto the surface of the drum, said air-film attracting to the surface certain constituents of the ore, and said surface causing the other constituents of the ore to rebound therefrom out of the sphere of action of the air-film, said casing inclosing the drum above and below and provided with separate receivers for the separated particles of the ore mass, and a wiper within the casing and supported below the drum and adapted to engage the surface thereof and remove adhering particles.
7. A process of separating ores which consists in delivering a body of ore containing particles having different degrees of cohesion and resilience upon an inclined surface and spreading the ore in a thin layer thereover and creating in proximity to said surface an air-film which induces the particles of inferior resilience and superior cohesion to adhere to said surface, and simultaneously rejecting the particles of superior resilience and inferior cohesion by causing them to rebound out of the sphere of action of said air-film.
